UNITED STATES PATENT OFFICE.

CHARLES P. DANKS, OF LAWRENCEVILLE, ILLINOIS.

DISINFECTING AND DEODORIZING DEVICE.

1,113,959.

Specification of Letters Patent.

Patented Oct. 20, 1914.

Application filed March 3, 1914. Serial No. 822,158.

To all whom it may concern:

Be it known that I, CHARLES P. DANKS, a citizen of the United States, residing at Lawrenceville, in the county of Lawrence 5 and State of Illinois, have invented certain new and useful Improvements in Disinfecting and Deodorizing Devices; and I do declare the following to be a full, clear, and exact description of the invention, such as 10 will enable others skilled in the art to which it appertains to make and use the same, reference being had to the accompanying drawings, and to the letters and figures of reference marked thereon, which form a part 15 of this specification.

This invention relates to a disinfecting and deodorizing device particularly adapted to be used in toilet bowls and the like, and the invention has for its object to provide 20 a removable disinfecting and deodorizing device to be removably placed and automatically held in proper position within the toilet bowl, the same being arranged in such manner that upon flushing of the bowl 25 the same is deodorized and disinfected.

With this object in view the invention consists in the novel construction of the coils and their co-acting parts so arranged and constructed to receive a filling of ab- 30 sorbent material which is first saturated with a disinfecting, antiseptic and deodorizing preparation, the character of the said preparation being immaterial as far as this invention is concerned.

35 Referring to the accompanying drawings: Figure 1 is a plan view of a toilet bowl partly in section illustrating the invention in operative position therein. Fig. 2 is a fragmentary vertical sectional view through 40 the rim of a toilet bowl illustrating the device in proper relative position, and Fig. 3 is a sectional view illustrating the spiral members of the device, the parts being broken away in order to enlarge the view.

45 Like numerals of reference indicate the same parts throughout the several figures in which—

1 indicates the device which comprises the long main coil 2 and the short auxiliary 50 coil 3, said short auxiliary coil 3 having its ends secured to the main long coil 2 in the manner as shown in Fig. 1. Along the outer side of the long coil 2 is a metal spring 4 which spring is passed longitudinally 55 through the coil 2 and being bent back upon itself passes longitudinally of the coil 2 on

the outside thereof in such manner that the spirals 5 of the coil 2 are received within the two sides 6 and 7 of the spring 4. In order to maintain the spring 4 in proper position a plurality of clips 8 are arranged at intervals thereon in the manner as shown in the accompanying drawing. The two coils 2 and 3 are provided with a filling 9 (Fig. 2) of some suitable absorbent mate- 60 rial which is saturated with a suitable de-odorizing, antiseptic and disinfecting prepara- 65 tion before the device is applied to the bowl 10, after which the two end metallic caps 11 are applied to the ends of the main 70 coil 2 in the manner as shown in the accom- 75 panying drawing to properly retain the ab- sorbent material 9 therein.

Having thus described the several parts of this invention its operation is as follows: 75 The device being ready for application to the bowl the same is inserted under the top edge or rim 12 thereof which, in modern plumbing devices of this character, is pro- 80 vided with a flush water passage 13 which 85 communicates with the bowl 10 by means of openings or ports 14 in such manner that upon flushing the bowl the water is led thereto at points around the edge thereof. The device being thus applied in the manner 85 as shown in Figs. 1 and 2 the natural spring 90 tendency of the main coil 2, which is en- 95 hanced by the spring 4 as heretofore de- 100 scribed, securely holds the device in proper position within the bowl as will of course 105 be apparent from an inspection of the ac- 110 companying drawing. The short auxiliary coil 3, however, being secured to the main coil 2, becomes bowed or curved in a direc- 110

Having thus fully described the inven-

tion its operation is entirely apparent from an inspection of the accompanying drawing taken in connection with the above specification.

5 What I claim as new and desire to secure by Letters Patent of the United States is:—

1. A device of the character described including a main coil, a relatively short auxiliary coil connected thereto intermediate the 10 ends of said main coil, a metallic spring embracing the said main coil longitudinally thereof and lying opposite to said auxiliary coil, a suitable filling of absorbent material for said main coil, and a suitable filling of 15 absorbent material for said auxiliary coil, said main coil and said auxiliary coil being oppositely bowed when in operative position, the surface of said main coil forming a closure for the ends of said auxiliary coil, substantially as described and for the purposes set forth.

2. A device of the character described including a main coil, a relatively short auxiliary coil connected thereto intermediate the 20 ends of said main coil, a suitable filling of

absorbent material for said main coil, and a suitable filling of absorbent material for said auxiliary coil, said main coil and said auxiliary coil being oppositely bowed when in operative position, the surface of said 30 main coil forming a closure for the ends of said auxiliary coil, substantially as described and for the purposes set forth.

3. A device of the character described including a main coil, a relatively short auxiliary coil connected thereto intermediate the 35 ends of said main coil, a suitable filling of absorbent material for each coil, the said two coils being adapted to be oppositely bowed in such manner that said auxiliary 40 coil extends into the space encompassed by the bowed main coil substantially as described and for the purposes set forth.

In testimony whereof, I affix my signature, in presence of two witnesses.

CHARLES P. DANKS.
